INTERFOLDING MACHINE

James J. Deloye, Neenah, Wis., assignor to International Cellucotton Products Company, Chicago, Ill., a corporation of Delaware

Application February 2, 1933, Serial No. 654,857
Renewed November 1, 1935

14 Claims. (Cl. 270—39)

This invention relates to an improved interfolding machine and has particular reference to a machine for interfolding paper sheets, particularly soft and thin crepe paper such as cleansing tissue.

5 The machine herein disclosed is of the type shown in the patent to J. A. Nichol No. 1,516,779, November 25, 1924, and improvements have been embodied in the said type of machine to better adapt the Nichol type of machine to the interfolding of tissue paper.

10 As above indicated, the main object of this invention is to provide a machine which is especially adapted, although not restricted, to the interfolding of thin, soft and flimsy tissue paper such as cleansing tissue which, because of its lightness and flimsiness is quite difficult to handle.

15 This main object is accomplished by various features of improvement described and illustrated in the following specification and accompanying drawings (11 sheets) and various other objects of the invention will become apparent from the specification and drawings.

In the drawings:

20 Fig. 1 is a side elevation.
Fig. 2 is an end elevation.

Fig. 3 is a section on the line 3—3 of Fig. 2.

25 Fig. 4 is a fragmentary sectional view of a portion of the mechanism shown in Fig. 3 but on an enlarged scale.

Fig. 5 is a section on the line 5—5 of Fig. 3, certain portions being broken away to more clearly illustrate the details of construction.

30 Fig. 6 is a plan section on the line 6—6 of Fig. 3.

Fig. 7 is a side elevation of certain mechanism for marking the interfolded stack of sheets to indicate bunches of a predetermined number of sheets.

35 Figs. 8, 9, and 10 are sections on the lines 8—8, 9—9, and 10—10 respectively of Fig. 7.

Fig. 11 is a side elevation on an enlarged scale of certain mechanism shown in Fig. 3 for controlling the removal of the interfolded sheets.

40 Fig. 12 is a section on the line 12—12 of Fig. 11.

Fig. 13 is a section on the line 13—13 of Fig. 11.

Fig. 14 is a section on the line 14—14 of Fig. 13.

Fig. 15 is a detail illustration of an eccentric adjusting device also shown in Fig. 3.

45 Fig. 16 is an enlarged detail illustration of a gripping jaw also shown in Figs. 3 and 4.

Fig. 17 is a section on the line 17—17 of Fig. 16.

Fig. 18 is a section on the line 18—18 of Fig. 5.

50 Fig. 19 is a plan section on the line 19—19 of Fig. 18, and Fig. 20 is a detail illustrating the

manner in which the interfolded material is inserted into the bite of the gripping jaws.

5 In the disclosed interfolding machine structure, two wide webs of the desired quality of paper; for example, soft, flimsy crepe paper are supplied to the machine from any suitable source. Also, it will be understood that the webs may be single or multi-ply, depending upon the kind of products to be interfolded.

One web designated A in Fig. 3 of the drawings is fed over a top guide roller 25 from which the web is directed over an anvil roll 26 with which a slitter 27 cooperates to divide the wide web longitudinally into two narrow webs. If desired, slitters similar to 27 may be provided for trimming the edges of the web, but such slitters may be omitted where the width of the webs supplied is not materially more than equal to two of the desired widths. On the opposite side of the machine, a similar web of paper designated 13 is fed over another anvil roll 26 with which another 10 slitter 27 cooperates to divide the web into two 15 narrower widths.

From the respective anvil rolls 26—26, the webs A and B travel downwardly between pairs of 20 cooperating feed rolls 28 and 29 respectively and around the respective rolls 29 and over rolls 25 30—30.

25 The respective webs A and B travel over the respective rolls 30—30 and downwardly between them, suitable guides 31—31 being provided for controlling the path of travel of the webs after they leave the said rolls 30—30. It will be observed that the webs A and B are brought together between the rolls 30—30 and are so maintained by the guides 31—31.

30 Each of the rolls 30 is provided with a pair of 35 grooves 32—32, these grooves being diametrically oppositely disposed. The grooves of one roll 30 are so arranged that they will come opposite the portions of the other roll 30 substantially mid-way between the grooves of such other roll. The surfaces of the rolls 30—30 are longitudinally unbroken and substantially smooth. Rotatable 40 cutters 33—33, each provided with a pair of diametrically oppositely disposed knives 34—34 are arranged to cooperate with the respective rolls 30, the arrangement being such that the knives 34 register with the grooves 32 of the respective rolls. Since cutter rolls act with the rolls 30—30, the 45 latter, for convenience may hereinafter be referred to as cutter rolls. It will be understood that by the described arrangement, the webs A and B will be alternately cut crosswise so that 50 one of the transversely extending cuts in the web 55

A will be disposed substantially mid-way between transversely extending cuts in the web B.

5 A pair of cooperating feed rolls 35 and 36 are provided for pulling the adjacent sheets through the guides 31—31. Gripping jaws 37 and a tucking device 38 cooperate to fold the sheets and insert them into stacking mechanism indicated at 39.

10 The above general explanation of the improved machine and its operation will serve to facilitate understanding of the following explanation of various details of construction.

15 There are two side frames 40 and 41 which are suitably united; for example, by means of a plurality of tie rods such as indicated at 42. Each side frame includes a plurality of relatively independent castings which are suitably united to form rigid side frames. At the upper end of each side frame, ways indicated at 43 and 20 44 are formed for slidably receiving bearing members such as 45 which rotatably support the cutter rolls 33 and bearing members such as 46 which rotatably support the cutter rolls 30.

25 As shown in Figs. 3, 5, and 18, the bearing blocks 46 rest on an upwardly projecting boss in the bottom of each way, and the cutter roll supporting bearings 45 are adjustably supported relative to the lower bearings 46. For adjustably supporting the upper bearings 45, a sort of screw 30 jack arrangement is provided which is best shown in Fig. 18. This supporting means includes a base element 47 which rests on the top of the bearing block 46 and is provided with a tongue and groove connection therewith as indicated at 35 48 for preventing relative rotation of the base member 47 and the lower bearing member 46. The base member 47 is bored out as indicated at 49 to receive the screw threaded stem 50 of a post which has a head 51 forming a seat on which the upper bearing member 45 rests. A nut 52 threadedly fits the post 50 and is rotatably seated on the upper end of the base 47. The lower edge portion of the nut 52 is provided with gear teeth as indicated at 53 which are adapted to be engaged by the teeth of an adjusting tool 54.

45 For positioning the adjusting tool 54 with respect to the gear teeth 53 of the nut, the base member 47 is provided with apertures such as 55 for receiving a stem portion 56 of the tool. It will be understood that by turning the tool 54, the nut 52 will be rotated so as to cause the headed post 50 to be adjusted upwardly or downwardly as desired. Rotation of the post 51 may be prevented by locking the head 51 of the post 55 to the upper bearing member 45, for example, by providing the head of the post 51 with a slot and the bearing 45 with an off-center pin (not shown) to enter such slot. A holding screw 57 threadedly engages an opening in the top end portion of the frame and the lower end of the screw engages a thrust member 58 which rests on the upper bearing 45. The screw 57 is turned down so as to tightly hold the upper bearing 45 in fixed, spaced relation (determined by the screw jack device) 60 to the lower bearing 46. By this arrangement, the cutter rolls 33 and 30 are maintained in accurately adjusted predetermined relation.

65 By removing the topmost casting elements which are normally held in place by bolts 59, the cutter rolls 33 and 30 may be easily removed from the machine.

70 The slitters 27 comprise disks having sharp edges, these disks being rotatably mounted in the forked ends of arms 60 which are secured to rods 61, the latter being rotatably supported at their

ends in suitable bearings formed in or carried by the topmost castings of the side frames. The slitter arms 60 are provided with upwardly and outwardly extending arm members 63 for maintaining the slitter disks 27 in operative relation 5 to their respective rolls 26.

The source of power

For effecting rotation of the cutter rolls 33, the rolls 30, and other parts of the machine, the following arrangement is preferred although it may obviously be radically modified. An electric motor 79 is disposed within the base area of the machine and it is coupled to a speed reducing unit which delivers its power through a shaft 80. 10 The shaft 80 is provided with a sprocket 81 from which power is transmitted to a double sprocket member 82 on a short, fixed shaft 83 suitably mounted on the frame 40. The double sprocket 82 includes a large sprocket wheel 84 and a small 20 sprocket wheel 85, a chain 86 passing around the sprockets 81 and 84. On the shaft 87 of one of the anvil rolls 30, there is mounted a sprocket wheel 88 which has connected to it a clutch mechanism 89, another portion 90 of which is suitably connected to the shaft 87 so that rotation of the sprocket 88 may be imparted to the shaft 89 through the clutch 89—90. A chain 91 transmits power from the sprocket 85 to the sprocket 88. The clutch 89—90 may be of any 30 conventional type, and in this instance it is shown as being controlled, i. e. engaged or disengaged, by means of a rock lever 92 pivoted intermediate its ends as indicated at 93 on a bracket 94 which is secured to the frame 40. One end of the rock 35 lever 92 is suitably connected as indicated at 95 to clutch operating means, and the other end of the rock lever has connected to it an operating rod 96 which extends transversely of the machine and is provided with a handle 97 on the 40 front side of the machine for facilitating manual adjustment of the clutch.

The shafts of each of the cutting rolls 33—33 and cutter rolls 30—30 at each end thereof and outwardly of the respective side frames, are provided with intermeshing gears for effecting rotation at properly correlated speeds. The two cutter rolls 30—30 are driven by means of gears 98 and 99 which intermesh as clearly indicated in Fig. 1. Similar gears are also provided on the 50 opposite side of the machine. The cutter rolls 33 which respectively cooperate with the cutter rolls 30 are each provided with gears 100—100 which respectively mesh with the gears 98 and 99 but not with each other. This arrangement is clearly 55 shown in Fig. 1.

The shaft of the slitter anvil roll 26 at the right hand end of the machine is provided with a gear 101 which meshes with the gear 100 of the adjacent cutter roll 33, and on the opposite side of 60 the machine, the shaft of said slitter anvil roll is provided with a sprocket 102. The shaft of the other slitter anvil roll on the same side of the machine is provided with a sprocket similar to the sprocket 102 and a chain 103 passing around 65 said sprockets serves to effect rotation in the same direction as both of the slitter anvil rolls 26.

The pairs of feed rolls 28 and 29 at each end of the machine are driven by gear connections to the respectively adjacent cutter rolls 30—30. As shown in Fig. 1, the shafts of the rolls 29 are provided with gears 104 which respectively mesh with the gears 98 and 99 of the cutter rolls 30—30, and the shafts of the outer rolls 28 are provided with 70 75

gears 105 which mesh with the gears 104 of the rolls 29.

The feed roll pairs 28-29

The pairs of feed rolls 28 and 29 are rotatably mounted in end brackets such as indicated at 106, the details of these brackets being best shown in Fig. 15. It will be seen that each bracket 106 includes a body portion 107 in which the inner roll 29 is journaled and a laterally extending bracket portion 108 through which a bolt passes for fastening the bracket to the side frame. The side frame is suitably recessed to receive the body portion 107 of the bracket.

The outer roll 28 is so mounted that it may be adjusted towards or from the roll 29. This is accomplished by rotatably mounting a sleeve or bearing bushing 109 in the bracket 106, the bracket being slit as indicated at 110 so that by tightening a bolt and nut 111, the bushing 109 may be locked in adjusted position. The shaft ends of the outer feed rolls 28 are journaled in bearing apertures 112 in the members 109 and the apertures 112 are slightly eccentric of the bushing as clearly indicated in Fig. 15. It will be evident that by rotating the bushing 109, the axis of the roll 28 may be moved outwardly or inwardly as desired. For facilitating adjustment of the bushing, a flanged portion 113 thereof is provided with radial recesses 114 which may be engaged by a suitable tool. The slight adjustment of the outer rolls 28 contemplated by the described eccentric mounting will not impair the driving engagement of the gears 104 and 105.

The surfaces of the rolls 28 and 29 are preferably knurled so as to provide a more effective grip on the tissue web which is fed by the said rolls.

The guides 31-31

The guides 31-31 are such that they loosely confine the adjacent webs within a desired path of travel, and there is a plurality of guides 31 disposed at longitudinally spaced intervals as will be understood by reference to Figs. 2, 4, and 5. The guides 31 on opposite sides of the paper web are of like construction, and hence the following explanation applies to each guide element.

All of the guides 31 are mounted on shafts such as 115 which are fixedly mounted in the side frames. Each guide 31 consists of an upper portion 116 and a lower portion 117. The lower portion is an elongated finger-like member having a head portion 118 bored out to fit the shaft 115 and split as indicated at 119 so that it may be clamped in fixed position on the shaft 115 by means of clamping screws such as 120.

The upper guide member 116 includes an upwardly extending finger or stripper 121 which is arcuately beveled as indicated at 122 at its free end to fit the surface of the cutter roll with which it cooperates so as to thereby effectively strip the paper web from the roll in the event that the paper should tend to cling to the roll. At its lower end, the stripper finger 121 is provided with a head portion 123 which straddles the head 118 of the lower guide member and it fits on the rod 115 so that the finger may be swung around the said rod. For normally maintaining the free end 122 of the stripper guide member in engagement with the surface of the roll 30, the weighted arm 124 extends outwardly from the head 123 and tends to swing the upper member in the required direction. Because of the length of the beveled roll-engaging surfaces 122 of the strippers 121, the stripper ends will bridge the grooves in the

rolls 30-30 without entering the same. However, as a precautionary measure, the rearward edge of each groove may be slightly chamfered as indicated in the drawings, to avoid any possibility of the joints of the strippers engaging the rearward walls of the grooves.

The feed rolls 35-36

The feed rolls 35 and 36 are rotatably mounted in suitable supporting brackets such as shown at 125, and the roller 35 is preferably mounted in said bracket through the agency of a bushing which is eccentrically bored out to receive the roll shaft. By this provision, the roller 35 is adjustable towards or from the roller 36 in substantially the same manner as the rollers 28 are adjustable relative to the rollers 29 as above explained.

As best shown in Figs. 2, 4, and 5, the rollers 35 and 36 are provided with grooves 126 for receiving the guide members 117-117. The rollers are adjusted relative to each other so that they will grip the webbing sheets between them and propel them downwardly as an incident to the rotation of the rolls. The surfaces of the rolls 35 are knurled as indicated in Figs. 2 and 5 to improve the feeding action of the rolls on the paper sheets. The rolls are rotated through the agency of idler gears 127, one being on each side of the machine and meshing with the respective gears 98. The shaft ends of the feed roller 36 are provided with gears such as 128 which mesh with the respective idler gears 127, and the shaft ends of the feed roller 35 are provided with gears such as 129 which mesh with the gears 128. Thus, the feed rollers 35 and 36 are driven in opposite directions, and it will be understood that the peripheral speed of rotation is the same for each roll, this being controlled by the use of the gears 128 and 129 of proper pitch diameter.

The gripping jaws and tucker (37 and 38)

The gripping jaws 37 and 38 of which there are two oppositely disposed sets or pairs, are operated from shafts 130 and 131, there being one of each of such shafts at each end of the machine.

The shaft 130 is in the form of a crank shaft as will be presently explained in greater detail, the ends of the shaft being suitably journaled in the side frames 40 and 41 as clearly indicated in Fig. 2. The ends of the shafts 130 project beyond the respective side frames and are provided with gears 132. The gears 132 of the shaft 130 at the right hand end of the machine as viewed in Fig. 1 mesh with the idler gears 127 through which rotation is transmitted to both ends of the shaft 130 from the gears 98 on the ends of the adjacent cutter roll 30. The gears 132 on the ends of the shaft 130 at the left hand end of the machine as viewed in Fig. 1 mesh with idler gears 133, and such idler gears mesh with the gears 99 on the respective ends of the shaft of the other cutter roll 30. Hence, rotation is imparted to the shaft 130 at the left hand end of the machine.

The shafts 131 are suitably journaled in the side frames 40 and 41 and one end of each of the shafts projects beyond the frame 40 and is provided with a gear such as 134. Idler gears such as 135 mesh with the gears 132 and 134 and serve to transmit rotation to the respective shafts 131.

Each of the jaws 37 includes upper and lower jaw members 136 and 137 respectively, these jaw members being of substantially the same length 75

as the cutter rolls 33, cutter rolls 30 and other parts as clearly shown in Fig. 5. For a purpose which will presently appear, the jaws are notched out at spaced intervals as indicated at 138. The 5 two jaw members are suitably pivotally connected on a shaft 139 on which they are positioned by means of end collars 140 which are fixedly secured to the shaft by means of set screws or otherwise as indicated in Fig. 16.

10 By reference to Figs. 6 and 16, it will be seen that the upper jaw is provided with bearing bosses 141 and that the lower jaw is provided with similar longitudinally spaced bearing bosses 142, all of these bosses being suitably bored out 15 to receive the pivot shaft 139. At one or both ends of the jaws, a hollow 143 is formed between semi-circular portions formed integral with the respective jaws and a coil spring 144 is disposed in said hollow space around the portion of the 20 pivot shaft 139 extending through such space. One end of the spring is anchored as indicated at 145 in the fixed collar 140 and the other end 146 of the spring engages a bridge portion 147 of the upper jaw and serves to normally urge said jaw into closed position relative to the lower jaw. The lower jaw is held in fixed position on the shaft 139 by suitable means such as set screws as indicated at 148 which extend through the lower 25 jaw bearing bosses 142 and engage the pivot shaft.

The jaw structures 37 may be termed floating jaws since they open and close with respect to each other and also travel through predetermined paths which in this instance are elliptical as indicated by dotted lines 149 in Fig. 4.

35 For imparting the elliptical travel movement to the respective jaw sets 37 and for opening the jaws against the force of the closing springs 144, the following arrangement is provided.

40 The bearing portions 142 of the lower jaw are provided with angularly upwardly extending bosses 150 to which adjustable tie rods such as 151 are secured. At their upper ends, the tie rods 151 are secured to bearing members such as 152 45 which fit rotatably on cranks 153 of the shafts 130 (see Figs. 2 and 4).

Between the bearing portions 141 and 142 of the upper and lower jaws, spaces are provided for receiving the bearing end portions 154 of connecting rods 155, the other ends of which are provided with bearing heads 156 which rotatably fit on cranks 157 formed on the shaft 131.

50 It will now be understood that by proper timing or synchronizing of the cranks 153 and 147, the respective jaw sets 37 may be propelled through the elliptical paths of travel 149.

For effecting opening of the jaws 37, the upper jaw is provided with bosses such as 158 which extend upwardly from the bearing portions 141 55 thereof and connecting rods 159 are secured at their lower ends to such bosses. The upper ends of the connecting rods 159 are provided with anti-friction rollers such as 160 which are adapted to engage cams like 161 carried by the crank 60 65 153 of the shaft 130.

It will be seen that so long as the anti-friction roller 160 engages the high peripheral portion 162 of the cam 161, the jaws 37 will be held open and that as soon as the rollers 160 leave the high 70 cam surface and engage the low surface portion 163, the jaws will be closed by the action of the springs 144. Obviously, the anti-friction roller 160 will roll around the cam 161 as an incident to the revolution of the cam about the axis 75 of the shaft 130. By properly setting the cam on

the crank shaft, the jaws will be caused to open and close in properly synchronized relation to other operations with which the jaws cooperate.

As best shown in Figs. 4 and 21, the tuckers 5 38 serve to tuck portions of the paper sheets into the bite of the jaws 37 when open. The tuckers 138 comprise arms 164 which are secured to shafts 165, the latter being suitably journaled in the side frames of the machine (see Fig. 6). The free ends of the tucker arms 164 are connected by means of an angle iron member 166 10 which supports a tucker blade 167. As indicated in the drawings (see Fig. 4), the blade 167 is a thin, flat strip which is adapted to enter between the open jaws 37 without occupying a material 15 amount of space.

The tucker arms 164 are caused to swing through a limited arc about the axis of the shaft on which they are mounted, this being accomplished by means of a suitable cam 168 which 20 acts on the free end 169 of an arm 170, the other end of which is secured to the shaft 165 as clearly shown in Figs. 3 and 6.

By reference to Fig. 3, it will be apparent that the path of travel of the forward edge of the respective tucker blades 167 will be slightly arcuate and that in its downward movement, the forward edge of the blade will move towards the paper web.

30 The cams 168 which control the tucker arms 35 are so proportioned that from the highest point of travel reached by the tucker blade 167, as shown in Fig. 4, the blade will move downwardly to a point substantially as indicated at 171 where it intersects the downward path of travel of the opposite jaw set. This path of travel is substantially as indicated by the dotted lines 172.

Further referring to Fig. 4, the operation of the tuckers and jaws may be described as follows:— The jaw set 37 at the right hand side of Fig. 4 is 40 shown slightly below the highest point of its elliptical path of travel. In the illustrated position, the jaw set mentioned may be said to have just started its downward path of travel in the direction indicated by the arrow 173. The oppositely disposed tucker member 38 has traveled through the initial portion of its path of travel and has just started to tuck the paper webs between the open jaws of the right hand jaw set. The cooperating tucker and jaw set move downwardly in 45 unison through their respective paths of travel until the path of travel of the jaw set leaves the path of travel of the tucker, whereupon the spring 144 is permitted to close the jaws to thereby effectively grip and continue to pull the folded sheets downwardly. It will be understood that 50 there is a slight relative movement between the cooperating tucker blade and jaw set during the described tucking operation, since during the initial portion of the downward movement of the 55 jaws, the tucker is forcing the paper sheets into the jaws while during a subsequent portion of the downward movement, the jaws are moving away from the tucker blade until the jaw actually leaves the blade. It is found that in the described operation, the tucker blade 167 will recede from the jaws without withdrawing with it 60 the paper webs.

The mechanism thus far described is so synchronized that the tucking members will engage 70 the adjacent web of paper substantially along the line at which it has previously been slit. Thus the sheets of paper are folded intermediate their lengths and the ends of the oppositely disposed sheets are located in the fold.

The stacking arrangement

As indicated in Figs. 3, 4, and 5, the interfolded sheets are stacked between oppositely disposed series of oscillating fingers 174-174. Each series of fingers comprises a plurality of like fingers which are secured in spaced relation to a shaft 175 which is journaled in suitable bearing brackets 176 mounted on the side frames. As clearly shown in Fig. 4, the fingers include tail portions 177 which have flat, smooth inside surfaces and head or hook portions 178 which are provided with outwardly facing bars 179.

Both series of fingers 174 are oscillated in unison, each series being actuated by an eccentric 180 mounted on the rotating shaft 131. The eccentrics 180 act through connecting rods such as 181 and arms 182, the latter of which are suitably fixed to the respective shafts 175. The eccentrics 180 are so set with relation to each other that the respective series of fingers 174 will be simultaneously oscillated in the same direction.

When the respective jaw sets 37 approach their lowermost position, they carry the folded paper web underneath the hooked ends 178 of the finger series and the arrangement is such that the paper is released from the jaws by opening of the latter approximately at the time the forward folded edge of the paper engages the inside faces 177 of the stacking fingers. It will also be evident that the stacking fingers 174-174 are continuously in movement owing to the eccentric actuating mechanism arrangement described, but that when the jaws carry the sheets into the bite of the stacking fingers, the jaws are in forwardly inclined position. When the edge of the sheet engages the inside face of the stacking fingers, the jaws begin their rearward oscillation. The entire stack of sheets between the stacking fingers is thus shifted back and forth and this shifting is highly desirable in that it tends to even out the stack so that it may be readily divided into bunches and packed in suitable boxes.

Sheet counting mechanism

To facilitate packing of a certain number of sheets in a box; for example, a cardboard box in which the sheets are sold at retail, the following mechanism is provided for counting the sheets and indicating points of division of the stack into bundles of a predetermined number of sheets.

In this instance, the counting mechanism about to be described is associated with the stacking fingers on the left hand side of the machine as viewed in Figs. 4, 6, and 7.

A bracket 183 is fixedly supported on a tie bar 184 which extends between the side frames of the machine and on the inner or free end of the bracket 183, there is rotatably mounted a disk 185 having associated with it a ratchet wheel 186. The ratchet wheel 186 is formed integral with or secured to the disk 185 so as to be maintained in fixed relation thereto. The ratchet 186 is provided with teeth corresponding in number to the number of sheets it is desired to package in a single box, or in the case of packages of small number of sheets, the ratchet may have multiples of the number of sheets. The disk 185 is provided with a notch 187 in its periphery.

The ratchet 186 and disk 185 are rotated step by step, one step for each sheet added to the stack. Such step by step rotation is effected through the agency of an arm 188 which is connected to the ratchet and disk element, and arm 189 which is secured at one end to the rock shaft

165 and has its other end connected by means of a link 190 to the free end of the arm 188 (see Figs. 3 and 6). The arm 188 is provided with a boss 191 on one side which is suitably bored as indicated at 192 to receive a plunger 193 having a tooth 194 adapted to engage the teeth of the ratchet 186. A spring 195 is provided for urging the plunger 193 into engagement with the ratchet.

It will be seen that each time the left hand tucker 164 moves upwardly, the arm 188 will be rocked in a clockwise direction as viewed in Figs. 3 and 7 and that the ratchet 186 will incidentally be advanced. The extent of movement imparted to the ratchet 186 may be adjusted to the desired amount by means of an adjustable connection indicated at 196 between the rock arm 189 and the link 190. A spring-pressed pawl 197 carried by a bracket arm 198 is provided for preventing back lash of the ratchet 186 as an incident to the rearward swinging movement of the arm 188.

An arm 199 is pivotally mounted as indicated at 200 on a portion of the bracket 183. This arm 199 is yieldingly pulled upwardly by means of a tension spring 201 connected between the arm as indicated at 202 and the end of the bracket 183 as indicated at 203. The arm 199 is provided with an upstanding lug 204 which carries a toothed element 205 which is adapted to ride on the periphery of the disk 185 and to drop into the notch 187 thereof, once for each turn of the disk. If it is desired to provide packages of a small number of sheets, the disk 185 may be provided with additional notches 187. In that case, the ratchet 186 will, of course, be modified to provide teeth in the desired multiples of teeth.

It will be understood that during the normal operation of the machine, the toothed element 205 will be in engagement with the periphery of the disk 185 so that it will hold the arm 199 in its lowermost position as illustrated in Fig. 3. In this position, a catch 206 carried by the arm 199 is below the path of oscillation of the lower end of an arm 207 which is fixedly secured to the oscillating shaft 175.

When the toothed element 205 drops into the notch 187, the catch 206 will be in position to engage the lower end of the arm 207, thereby to prevent rocking of the stacking fingers 174 in counterclockwise direction as viewed in Fig. 7. The fingers 174 being thus held stationary while the jaw set 37 continues its normal operation, it will be evident that the edge of the folded paper brought under the hooks 178 will engage the inside faces of the fingers 174 and be upset substantially as indicated at 208 in Fig. 7. Such upsets form clearly visible marks in the stack of sheets and readily indicate where the stack should be separated to form bundles of the desired number of sheets.

To permit the left hand series of stacking fingers 174 to be locked in the described position, for marking the sheets, the connecting rod 181 which normally transmits oscillating movement to the fingers from the eccentric 180 is of special construction, which is best shown in Fig. 10. The arrangement as shown in Fig. 10 includes an eccentric collar 209 which is provided with a boss 210 bored out and threaded to receive a sleeve 211. A lock nut 212 serves to normally hold the sleeve 211 in adjusted position relative to the eccentric collar 209. The sleeve 211 is bored out so as to provide an internal shoulder 213 on which the head 214 of a stem element 215 may

seat. The frame 215 fits slidably in the sleeve opening portion 216 and a spring 217 disposed within the sleeve between the head 214 of the stem, and the eccentric collar serves to normally transmit power from the eccentric collar to the stem 215. The stem 215 has secured to its outer end a suitable end member 218 which is connected to the arm 182. It will be seen that when the stacking fingers 174 are locked against oscillation by the above described means, the eccentric element may continue its normal operation while the arm 182 remains stationary. The relative movement between the eccentric member 209 and the arm 182 is then taken up by compression of the spring 217.

For facilitating adjustment of the depth or extent of upset produced by the described arrangement, the catch element 206 is adjustably mounted on the arm 199. As shown in Fig. 9, the catch element 206 is provided with a dovetailed sliding connection with the arm 199 and it is adapted to be adjusted longitudinally of the arm by means of a rod 219 which has threaded engagement with the base portion of the catch member. The outer end of the rod 219 is rotatably supported in a lug 220 formed integral with the bearing end 200 of the arm 199 and adjustment of the rod 219 may conveniently be effected by means of a hand wheel 221 suitably supported for rotation and connected to the outer end of the rod by means of a universal joint 222.

The stacking, receiving, and handling mechanism

As clearly shown in Fig. 3, the interfolded sheets are guided between the oscillating fingers 174 and enter a conveyor 223 which conveys the stack of interfolded sheets to one end of the machine as indicated at 224 (Fig. 1).

The feed movement of the stack of sheets is controlled by a traveling bottom in the guide which comprises a plurality of chains 224 which are advanced step by step. The chains 224 are supported by sprockets 225 on a shaft 226 in the delivery end of the conveyor and by sprockets 227 on a shaft 228 near the receiving end of the conveyor. The shaft 226 is rotatably mounted in suitable brackets 229 carried by the frames 40 and 41 and the shaft 228 is rotatably mounted in suitable bearing brackets 230 also mounted on the frame sides 40 and 41.

For advancing the conveyor chains 224, it is preferred that means be provided whereby the speed of the feed movement may be accurately controlled. In this instance, the means provided includes an eccentric 231 mounted on the shaft 131, a collar 232 embracing and actuated by the eccentric, a connecting rod 233, a rock lever 234, ball clutch mechanism 235, and intermeshing gears 236 and 237. The gear 237 is mounted on 60 and keyed to the shaft 228 and the gear 236 is connected to one of the elements of the clutch 235.

The structure of the clutch 235 is best illustrated in Figs. 13 and 14. As there illustrated, the structure includes inner and outer clutch members 238 and 239 respectively, the outer member providing an internal clutch face 240. The inner member 238 is formed somewhat in the manner of a ratchet wheel so as to provide a series of substantially flat cam faces 241. Rollers 242 are positioned between the respective cam faces 241 and the oppositely disposed portions of the internal clutch face 240, and by rotation of the outer clutch member 239 in one direction (counterclockwise, as shown in Fig. 14), the

rollers 242 will be jammed between the cam faces 241 and clutch face 240, and thereby transmit rotation to the internal clutch member 238. The rollers 242 are loosely confined in operative relation to the respective cam faces by means of pairs of cross pins 243 which are carried by retaining plates 244 and 245. The retaining plate 245 is seated on a shoulder 246 formed on the inner clutch member 238 so as to thereby maintain the pins 243 in the desired position from the axis of the clutch mechanism. Plungers such as indicated at 247, urged outwardly by light springs such as 248, are provided in the inner clutch member 238 and serve to normally maintain the rollers 242 in contact with the oppositely disposed faces between which they are jammed for transmitting movement from the outer to the inner member.

As shown in Fig. 14, the plungers act against one of the cross pins 243 to thereby effect relative movement between the pin carrying plates 244 and 245 and the pins carried thereby, whereby the rollers are normally maintained in the said position. The springs 248 are sufficiently light so that they will not maintain the rolls 242 in such tight engagement between the inner and outer clutch faces that reverse movement of the outer clutch member can be transmitted to the inner member. Of course, the resistance of the stack of sheets and the frictional resistance of the conveyor mechanism tends to resist rearward movement.

The outer clutch member 239 has connected to it the arm member 234 so that oscillation of the arm as produced by the eccentric 231 will be imparted to the outer clutch member and thereby, in one direction only to the inner clutch member. The gear 236 is suitably secured to the inner clutch member and hence the step by step feed movement of the inner clutch member will be transmitted to the gear 237 and the conveyor chains 224.

For facilitating adjustment of the extent of feed movement imparted by the described mechanism, the connecting rod 233 is adjustably connected to the clutch arm 234 through the agency of a bearing block 249 which is slidably mounted between the forked portions of the arm 234 as clearly shown in Fig. 11. The block 249 is adapted to be adjusted lengthwise of the arm 50 by means of a screw 250 which threadedly engages an aperture 251 in the end of the arm 234. The inner end of the screw 250 is anchored to the block 249 in any suitable manner to permit rotation of the screw 250 relative to the block 55 but to cause the block to follow the screw inwardly or outwardly. A lock nut 252 may be provided on the screw 250 for locking the same in the desired position of adjustment.

A hand wheel 253 is secured to one end of the shaft 228 for facilitating manual feed of the conveyor chains 224 when it is desired to empty the conveyor 223 or for any other purpose. It will be understood that the conveyor may readily be manually advanced since the clutch mechanism 65 235 permits the gears 237 and 236 to be advanced independently of the outer clutch member and arm 234.

General remarks

The principle of the Nichol patent before alluded to is, of course, retained in the above described mechanism, but the various elements of the mechanism have been modified so as to particularly adapt the mechanism to the successful 75

interfolding of light-weight, flimsy tissue paper which could not be successfully folded on the Nichol patent machine. In the described structure, the mechanism is arranged to divide a wide sheet of material into two narrower sheets and to simultaneously interfold the narrow webs to thereby form two stacks of interfolded sheets. Hence, the machine described may be said to be a double machine. Obviously, the mechanism may be restricted to a single machine or it may be extended to form machines for simultaneously interfolding more than two webs.

The various elements of mechanism are synchronized in their operative relation by the various gear connections described and it will be understood that in order to obtain accurate timing and freedom from play, accurate driving connections are desirable. It is preferred that the intermeshing gears 98-99 and 100-100 be formed of two sections as indicated in the drawings and the two sections adjustably connected so that play incident to wear may be taken up by appropriate adjustment of the gears. For facilitating manual adjustment of the mechanism as a whole to any predetermined or desired position for any purpose whatever, a hand wheel 254 is connected to one end of the main driving shaft 87.

Changes in the described structure may be made without departing from the spirit of the invention, the scope of which should be determined by reference to the following claims, the same being construed as broadly as possible consistent with the state of the art.

35 I claim as my invention:-

1. In a machine of the class described, the combination of means for transversely severing a web of paper at longitudinally spaced intervals, said means including a cutter roll, means for feeding the web to said roll, means for withdrawing the web from said roll, said feeding and withdrawing means being operated to feed the web and withdraw the web at substantially the same speed so as to maintain the web under predetermined tension on the cutter roll, said feeding means including a pair of rolls, eccentric means for mounting one of said rolls for adjustment towards or from the other, and means interconnecting said rolls for rotation at the same 50 peripheral speed.

2. In a machine of the class described, the combination of means for transversely severing a paper web at longitudinally spaced intervals, means for feeding the web to said severing means, said feeding means comprising a unitary structure including end members adapted to be fixedly mounted on the machine, and a pair of cooperating rolls rotatably mounted in said end members.

3. In a machine of the class described, the combination of means for transversely severing a paper web at longitudinally spaced intervals, means for feeding the web to said severing means, said feeding means comprising a unitary structure including end members adapted to be fixedly mounted on the machine, a pair of cooperating rolls rotatably mounted in said end members, and means for mounting one of said rolls in said end members for adjustment towards and from the other roll.

70 4. In a machine of the class described, the combination of means for transversely severing a paper web at longitudinally spaced intervals, means for feeding the web to said severing means, said feeding means comprising a unitary structure including end members adapted to be fix-

edly mounted on the machine, a pair of cooperating rolls rotatably mounted in said end members, and eccentric means for mounting one of said rolls in said end members for adjustment towards and from the other roll.

5 5. In a machine of the class described, the combination of means for transversely severing a web of paper at longitudinally spaced intervals, said means including a roll having a longitudinally unbroken, smooth surface, means for folding the severed sheets, and means for stripping the sheets from the roll and guiding the same to said folding means, said stripping means comprising a member provided with a beveled edge adapted to engage the roll surface, means for pivotally mounting said stripper member, and means for yieldingly urging said stripper member into engagement with the roll surface.

6 6. In a machine of the class described, the combination of means for transversely severing a web of paper at longitudinally spaced intervals, said severing means including a roll, means for folding the severed sheets, and means for stripping and guiding the sheets from said roll including a plurality of spaced stripper fingers having beveled ends adapted to engage the roll surface, means for pivotally mounting said fingers, means for yieldingly urging said fingers into engagement with said roll surface, and fixedly mounted guide fingers constituting continuations 30 of said pivotally mounted strippers.

7 7. In a machine of the class described, the combination of means for transversely severing a web of paper at longitudinally spaced intervals to divide the web into sheets, means for folding said sheets including a pair of gripping jaws and means for tucking the sheets into the bite of said jaws, said jaws comprising upper and lower members, means pivotally connecting said jaw members, and coil spring means disposed concentric with the axis of the pivotal connection between the jaw members for normally closing the same.

8 8. In a machine of the class described, the combination of means for transversely severing relatively independent webs of paper at longitudinally spaced intervals to divide said webs into sheets, means for interfolding the sheets of the respective webs including a pair of jaws and a tucker for tucking the sheets into the 50 grip of the jaws, means for propelling the jaws downwardly and outwardly, means cooperating with said jaws for withdrawing the sheets from the jaws and stacking the interfolded sheets, said means comprising a pair of oppositely disposed fingers having retaining hooks at their upper ends, said jaws being adapted to feed the folded sheet portions beneath the hook of one of said fingers and means for oscillating said fingers in unison to produce a weaving movement in 60 the stack of sheets whereby to produce evenness in the stack, and means for temporarily locking one of said fingers in predetermined position and at predetermined intervals for effecting upsetting of a folded sheet delivered to such fingers, thereby to form visible marks dividing the stack into sections containing predetermined numbers of interfolded sheets.

9 9. In an interfolded machine of the class described, means for transversely severing a pair of 70 paper webs at longitudinally spaced points to divide such webs into sheets, means for interfolding the sheets of the respective webs including jaws adapted to propel the folded sheets through predetermined paths of travel, means for re- 75

- ceiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
10. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
20. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
30. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
40. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
45. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
50. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.
55. In an interfolding machine of the class described, means for transversely severing a pair of paper webs at longitudinally spaced points to divide such webs into sheets, means for interfolding the sheets of the respective webs including jaws adapted to propel the folded sheets through predetermined paths of travel, means for receiving the interfolded sheets from the jaws and stacking the same, said means including a finger having a hook at its upper end, means for pivotally mounting said finger intermediate its ends, means for oscillating said finger about its pivot including an arm connected to said finger, a cam device and means connecting the cam device and said arm including a yieldable element for transmitting movement from said cam device to said arm, and adjustable means for temporarily locking said finger in predetermined position at predetermined intervals for effecting upsetting of the interfolded sheet delivered thereto by said jaw, said yieldable means serving to permit continued normal movement of the cam means while said finger is locked in said predetermined position.

locking means including a latch member, positioning means engaged by said latch member for normally maintaining the latter in inoperative position, said positioning means having means for causing said latch to move to operative position, and means for actuating said positioning means each time said interlocking means delivers a sheet to the stacking means.

12. In an interlocking machine of the class described, the combination of means for transversely severing a pair of paper webs at longitudinally spaced intervals to divide the webs into sheets, means for interlocking the sheets of the respective webs, a stacking mechanism for receiving the interlocked sheets from the interlocking means, a chute for receiving the stack from said stacking means, a conveyor for supporting the stack of sheets in said chute, means for advancing said conveyor step by step, and adjustable means for regulating the extent of movement imparted to said conveyor at each step, whereby the position of the top of the stacked sheets relative to the stacking mechanism is maintainable substantially constant.

13. In an interlocking machine of the class described, the combination of means for transversely severing a pair of paper webs at longitudinally spaced intervals to divide the webs into sheets, means for interlocking the sheets of the respective webs, a stacking mechanism for receiving the interlocked sheets from the interlocking means, a chute for receiving the stack from said stacking means, conveyor means for supporting the stack of interlocked sheets in said chute, means for advancing said conveyor step by step including a ball clutch device including a laterally extending arm, means for rocking said arm to actuate said conveyor through said clutch, said means including a cam device and a connecting rod for transmitting movement from said cam device to said arm, and an adjustable connection between said connecting rod and arm whereby the extent of movement imparted to said arm and to said conveyor may be adjusted.

14. In a machine of the class described, the combination of means for transversely severing a web of paper at longitudinally spaced intervals, said means including a roll having a longitudinally unbroken, smooth surface, means for folding the severed sheets, and means for stripping the sheets from said roll and guiding the sheets to said folding means, said stripping means comprising a member provided with a bevel edge adapted to engage the roll surface, means for mounting said stripper member so as to permit said bevel edge to follow the surface of said roll, and means for yieldably urging said stripper member into engagement with the roll surface.

JAMES J. DELOYE.
